PROTECTIVE SHEATH FOR A DRY SHAVER

Florian Seiffert, Glashutten, Taunus, Germany, assignor
to Braun A.G., Frankfurt am Main, Germany

Filed June 8, 1970, Ser. No. 23,352

Claims priority, application Germany Dec. 12, 1969

Term of patent 14 years

Int. Cl. D3—99

U.S. Cl. D87—1

Fig 1

Fig 2

Fig 3

Fig 4

FIG. 1 is a front elevational view of a protective sheath for a dry shaver showing my new design, the rear view being identical to the front shown;

FIG. 2 is a side elevational view thereof;

FIG. 3 is a bottom plan view thereof; and

FIG. 4 is a top plan view thereof.

I claim:

The ornamental design for a protective sheath for a dry shaver, substantially as shown and described.
